LUIGI SALADINO, OF BROOKLYN, NEW YORK.

SAFETY DEVICE FOR WINDOWS.

1,162,517.

Specification of Letters Patent. Patented Nov. 30, 1915.

Application filed June 8, 1915. Serial No. 32,880.

To all whom it may concern:

Be it known that I, LUIGI SALADINO, a subject of the King of Italy, and a resident of Brooklyn, in the county of Queens and State of New York, have invented new and useful Improvements in Safety Devices for Windows, of which the following is a specification.

This invention relates to a safety device for windows and has as its principal object to provide means whereby any operation to be performed on windows, such as cleaning, repairing, etc., may be done conveniently and without the danger to the operator of falling out of the window.

A further object of my invention is to provide a device of the character described, which is adjustable in width and height so as to adapt itself to any window of ordinary size.

A still further object is to provide a device which can be used as a screen and as a guard against children falling out of the window.

With the foregoing and other objects in view, my invention consists in the particular construction, arrangement and combination of parts hereinafter more specifically described and illustrated in the accompanying drawing, in which:

Figure 1 is a front elevational view of my device without the screen part thereof. Fig. 2 is an end view of the same. Fig. 3 is a front elevational view of the screen part of my device. Fig. 4 is an end elevational view of my device as applied to a window, showing the latter and adjacent parts of a wall partly in section and partly in elevation. Fig. 5 is a plan view of a chair forming part of my device, detached from the latter.

The same part is designated by the same reference character throughout the several views.

Referring more particularly to the drawing, 8 is a frame composed of four identical rectangular members such as 9, connected to each other by screw bolts 10 and wing nuts 11. The bolts 10 are passed through slots 12 formed in the overlapping ends of the members 9 so as to allow the extension and contraction of the frame, within certain limits, in both width and height. A ring 13 provided with wire netting 14 is connected by straps 15 of adjustable length to the corners of the frame 8 for purposes which will hereinafter appear.

Connected to the frame 8 by hinges 16 is a

chair 17 consisting of two substantially U-shaped frame sections 18 and a seat 19 made of wire netting attached, at its two ends, to the respective portions of the frame sections 18 by means of springs 20; depending legs 21 are mounted in the frame sections 18, one in each end thereof, altogether four legs.

22 is a frame similarly constructed as the frame 8, having applied to it a screen 23 divided into two equal sections, the upper end of each being secured to the respective members of the frame 22 and the lower end of each attached to spring-actuated rollers 24 rotatably mounted on the respective members of the frame 22, as clearly seen in Fig.

3. Owing to this arrangement, the frame 22 can also be extended and contracted in both directions. In the case of lateral extension, the sections of the screen 23 come apart at the center, as shown in the drawing. In the other direction, the rollers automatically yield when the frame is extended and wind the screen up when it is contracted.

Screw eyes 26 are provided on the frame 8 to each of which are attached a longer and a shorter link, 27 and 28, respectively, each having a hook 29 at its end. In the same manner, links 30 with hooks 31 are attached to the front edge of the chair 17. Staples 32 are provided in the window sill 33, near the inner edge thereof, adapted to engage the hooks 31 and similar staples 34 at the outer side of the window frame, adapted to engage the hooks 29.

For using the device in window cleaning, repairing or other outside work, I place the chair 17 on the window ledge 35, attaching the hooks 31 to the staples 32. The frames 8 and 22, secured together by screws or rivets passed through holes 25 provided in each corner of the frames for that purpose, are erected vertically on the chair 17 and hooked to the staples 34 by the longer links 27. A person cleaning or repairing the windows at the outside may thus conveniently be seated on the chair during the operation and be entirely protected from falling out of the window by the frames, the straps 15 and ring 13 being sufficient for this purpose, even if the screens would not hold the person back. If the work to be done requires the operator to stand erect, he may fasten around his waist a belt 36 attached by chains 37 to the upper members of the frame 8 and 38 provided with straps 38 adapted to be buckled over the shoulders. Links 39 at

tached to the belt and provided with hooks 40 at their ends, serve for the purpose of securing the belt to staples to be provided in the window frame as an additional security. 5 When used as a window guard and screen, the chair will be folded up on its hinges and secured in its erect position by a strap 41 attached to the ring 13. The frames are then secured within the window frames, attached thereto by means of the shorter links 10 28 hooked into the staples 34.

It is understood that while I have thus shown and described the preferred form of embodiment of my invention, I do not want 15 to be limited to its mechanical details, but may resort to such alterations and modifications as come within the scope of the claims 18 hereunto appended.

I claim:

20 1. A window-guard comprising, in com-

Copies of this patent may be obtained for five cents each, by addressing the "Commissioner of Patents, Washington, D. C."

bination; a frame consisting of four rectangular sections detachably and adjustably connected to each other, a ring maintained in the center of said frame, four straps of adjustable length connecting said ring to 25 the four corners of said frame and means for removably attaching said frame to a window-frame, substantially as and for the purpose set forth.

2. The combination with a window guard 30 frame of adjustable width and height,—of a chair comprising two separate seat-frame sections, a seat section resiliently connected thereto, and legs attached to the seat-frame sections, substantially as and for the purpose 35 set forth.

LUIGI SALADINO.
